UNITED STATES PATENT OFFICE.

WILLIAM G. BLOSS, OF LOS ANGELES, CALIFORNIA.

WAVE MOTOR.

Application filed July 15, 1925. Serial No. 43,728.

My invention relates to wave motors, and the general object thereof is to provide a wave motor of improved construction with increased power and efficiency.

5 A more particular object is to provide a wave motor with a relatively long stroke whereby increased power may be attained.

10 A further object is to provide a wave motor which may be mounted on the ocean bed under a pier between the piles thereof, with its wave plunger at an angle or parallel to the ocean bed, so that the waves will effect the upward power stroke of the plunger, to drive machinery on the pier, while the 15 downward stroke of the plunger will be effected by gravity.

Other objects and advantages will appear hereinafter, and while I show herewith and will describe a preferred form of construction, I desire it to be understood that I do not limit myself to such preferred form, but that various changes and adaptations may be made therein without departing from the spirit of my invention as hereinafter claimed.

25 Referring to the annexed drawing, which forms a part of this specification, and in which my invention is illustrated.

Fig. 1 is a side elevation of my wave motor shown mounted on the ocean bed along 30 the shore under a pier and between the piles thereof.

Fig. 2 is a horizontal section of my wave motor taken on line 2—2 of Fig. 1.

Fig. 3 is a cross section of one of the 35 plunger rollers taken on line 3—3 of Fig. 2.

Corresponding reference characters designate corresponding parts in all the views of the drawing.

40 A concrete base 1 is laid on the ocean bed adjacent the shore under a pier 2, between the piles 3 thereof, the base inclining downwardly from the shore into the ocean. A pipe 4 is embedded in the base 1 extending through the base from the upper to the lower 45 edges thereof. Vertical shafts 5 are journaled in bearings 6 on the inner sides of the piles 3 and extend upwardly through the floor 7 of the pier. Pinions 8 are carried on the lower ends of the shafts 5.

50 A wave plunger 10 includes a rectangular plunger frame 11, shafts 12 secured at their ends in side beams 13 on which shafts said plunger frame is mounted, rollers 14 journaled on said shafts 12 to roll on the foundation 1, flanged wheels 5, also journaled on said shafts, and tracks 16 supported on said

foundation on which tracks said flanged wheels travel. Racks 17 are provided on the outside of the beams 13 in mesh with the pinions 8. Sleeves 18 are placed on the 60 shafts 12 to which sleeves the side rails 19 of the plunger frame 11 are secured, whereby said frame is mounted on said shafts. In each roller 14 is fitted a bushing 20 through which the shaft 12 extends and which turns 65 on the shaft. One of the rollers 14 is journaled on each shaft 12 between the two sleeves 18 on said shaft, the ends of the bushing 20 of the roller abutting against the inner 70 ends of said sleeves and confining the roller 75 in a centrally disposed position on the longitudinal axis of the plunger frame. The hubs 21 of the flanged wheels 15 engage at one end the inner sides of the side beams 16. The other rollers 14 are journaled on the 80 shafts 12 between the flanged wheels 15 respectively and the sleeves 18 nearest said wheels, the bushings 20 of said rollers engaging at their ends the inner ends of the wheel hubs 21 and the outer ends of said 85 sleeves 18 respectively.

A sheave 25 is journaled in a bracket 26 secured on the lower edge of the foundation 1, the sheave resting just above and beyond the lower end of the tube 4. A cable 27 is 85 secured at one end to the lower end of the plunger frame 11 at 28 and extends under the sheave, through the tube 4, over sheaves 29 and 30 and is wound at its other end around the drum of a spring motor 31 operatively mounted on a power shaft 32, there being a ratchet 33 on said shaft engaged by a pawl 34 for preventing backward rotation of the shaft upon the unwinding of the motor under the influence of its 90 spring.

The inner end of the plunger frame 11 is connected to the piston rod 35 of a pump 36.

On the upper ends of the vertical shafts 5 above the pier floor 7 are loosely mounted bevel gears 37 which mesh with bevel gears 38 on a power shaft 39 journaled in bearings 40 secured to the floor of the pier. Ratchets 41 are secured on the upper ends of the shafts 5 above the pier floor 7, which ratchets are engaged by pawls 42 pivoted on the bevel gears 37 for preventing backward rotation of the bevel gears 37 and 38, and shaft 39.

The series of pinions 8 mounted on the 110 anchored vertical shafts 5 and meshing with the horizontally directed teeth of the racks

17 at each side of the motor, form supplemental guiding means which aid in preventing lateral shifting of the wave propelled parts.

18 The teeth of said racks are arranged to extend vertically so as to mesh properly with the teeth of the pinions on the vertical shafts. The teeth of said racks are of sufficient length to maintain proper engagement with the teeth of said pinions at all times, notwithstanding the fact that the inclination of the racks causes the teeth thereof to move up and down to some extent as the wave propelled frame advances and recedes.

19 In operation the waves W of the ocean act upon the plunger frame 11 to force the plunger upwardly, the rollers 14 rolling on the foundation 1 and the wheels 15 rolling 20 on the tracks 16. Said upward movement of the plunger operates the pump 36 through piston rod 35, and drives the power shaft 32 in one direction and permits spring motor 31 to wind up cable 27. The upward movement 25 of the plunger also causes the racks 17 to rotate the pinions 8 and vertical shafts 5 in one direction, which shafts, through the bevel gears 37 and 38, cause the power shaft 39 to rotate in one direction.

30 The plunger moves backwardly by gravity. During said movement the spring motor 31

unwinds its spring and cable 27 operates its drum, while the pawl 34 and ratchet 33 cause rotation of power shaft 32. During the return movement of the plunger the pawls 42 and ratchets 41 prevent backward rotation of bevel gears 37 and 38, and power shaft 39.

35 Hence one or the other of shafts 32 and 39 are being rotated for power transmission 40 whether the wave-propelled element is advancing or receding, thus providing a nearly continuous supply of power.

45 Having thus described and illustrated my wave motor, I claim:

50 In a wave motor, an inclined wave-propelled frame, wheels to support said frame, an inclined base whereon said wheels travel, inclined racks mounted in fixed relation to said frame, the teeth of said racks projecting laterally with respect to said frame, said teeth being at such an angle with respect to the racks as to adapt them for meshing with pinions having vertical axis, pinions in mesh 55 with said racks, vertical shafts on which said pinions are mounted, and fixed bearings for said shafts, said pinions being elongated in order to maintain engagement with said inclined racks while the latter advance and recede.

WILLIAM G. BLOSS.
